[57] CLAIM

The ornamental design for an electric vacuum cleaner,
as shown and described.

DESCRIPTION

FIG. 1 is a front, top, and right side perspective view of
an electric vacuum cleaner showing our new design;
FIG. 2 is a front elevational view thereof;
FIG. 3 is a rear elevational view thereof;
FIG. 4 is a right side elevational view, the opposite side
being a mirror image thereof;
FIG. 5 is a top plan view thereof; and
FIG. 6 is a bottom plan view thereof.

FIG. 1

FIG. 2

FIG. 3

FIG. 4

FIG. 5

FIG. 6
